UNITED STATES PATENT OFFICE.

JOHN HAHN, OF LOS ANGELES, CALIFORNIA.

PUMP-FITTING.

1,021,188.

Specification of Letters Patent. Patented Mar. 26, 1912.

Application filed June 20, 1910. Serial No. 568,033.

To all whom it may concern:

Be it known that I, JOHN HAHN, a citizen of the United States, residing at Los Angeles, in the county of Los Angeles and State of California, have invented a new and useful Pump-Fitting, of which the following is a specification.

This invention relates to a device adapted to be applied at the top of a deep well to facilitate the installation, operation and repair of the pump, and it includes means adapted for use in installing, operating, removing and replacing casing, pump tubing and sucker rods in and from wells.

With pump fitting of the kind heretofore in use to lower and elevate portions of pumping apparatus within the containing well-casing or pump tubing, it is necessary to remove such fittings after each operation, as they form no part of the permanent pumping apparatus, thus causing expense and loss of time.

An object of this invention is to provide an appliance whereby the well-driller and pump-man may handle the casing, the tubing and sucker-rods of pumps with greater ease and facility than has heretofore been possible; and which appliance is adapted in part to form, when desired, a permanent tubing-head or a permanent coupling between parts of the pumping apparatus; and is also adapted in part to form detachable clamping members, which may be quickly thrown out of operating position and subsequently removed without disturbing such coupling parts of the pumping apparatus.

A further object is to provide an appliance which will prevent the liability of dropping the sucker-rod or tubing into the well during the process of lowering and elevating the same and to provide a wrench to hold the sucker-rod and the tubing from unscrewing when the upper section of the sucker-rod is being screwed or unscrewed.

The invention is adapted to be constructed in different sizes and proportions, and may be thus fitted for use in connection with well-casing in some instances and with well-tubing in other instances.

The invention may be embodied in different forms.

The accompanying drawings illustrate the invention as applied for handling sucker rods and pump tubing, and for use as a permanent pump head coupling.

Figure 1 is a side elevation of apparatus

embodimenting the invention in use with parts in positions that may occur in the act of pulling the sucker rod, the polishing rod of which has been drawn out of the coupling, 60 the pump head having been unscrewed and drawn up with the polishing rod. Fig. 2 is a fragmental perspective view of the appliance constructed and applied to use for handling the sucker rod invented by me and 65 described and claimed in my application for Letters Patent of the United States, Serial Number 554,063, filed April 7, 1910. Fig. 3 is a fragmental vertical section of the parts of the apparatus shown in Figs. 1 70 and 2. Fig. 4 is a perspective view of the clamp jaw shown in Figs. 1, 2 and 3, which is adapted for engaging the ribbed sucker rod. Fig. 5 is a fragmental vertical section on line x^y , Fig. 6 of the apparatus embodying the invention as applied for use as a frictional tubing catcher. Fig. 6 is a fragmental plan of the tubing catcher shown in Fig. 5. Fig. 7 is a view of the pump head shown in Figs. 1, 2 and 3; the catcher jaws 80 being removed and the stuffing box and the polishing rod section of the sucker rod being shown in place.

The tubing-head or coupling 1 is provided on diametrically opposite sides with pivots 85 2 and on other diametrically opposite sides midway between the pivots 2 with orifices 3 formed in a projecting rim 4 preferably internally beveled and is also provided internally with a screw-threaded socket 5 at the 90 lower end and a screw-threaded socket 6 at the upper end and with an inwardly projecting shoulder 7 between the sockets 5 and 6. The pivots 2 are adapted to receive an elevator bail 8 by which the coupling-head 95 1 may be handled in lowering, elevating, screwing and unscrewing it. The orifices 3 are adapted to receive and loosely fulcrum detachable levers of the first-class comprising handles 9 of any desired shape and 100 comprising tapered, wedge-shaped clamping jaws 10. The lower screw-threaded socket 5 is adapted to screw onto the tubing 11 and the upper screw-threaded socket 6 is adapted to seat the pump head 12. 105

Two forms of clamping jaws are shown in the drawings. The form 10 being adapted for supporting the ribbed sucker rod 13, described in my said former application, and which rod is provided at its upper end 110 with a head 14 in which the ribs terminate. Said jaws 10 are provided with tapered

faces forming recesses 15 to loosely fit the longitudinal ribs 16 of the sucker rod, but said recesses are insufficient to allow the head 14 to pass the jaw so that when a pair of the jaws 10 is in place in the coupling-head, their handles being inserted through the orifices 3, the jaws, when closed, will allow the sucker rod 13 to slide freely up and down and will not allow the head 14 to pass downward past the jaws. The handles 9 are bent and afford a pivot space 17 between the top of the handle and the top of the jaw to accommodate the bars 4" formed by rim 4 and are perforated to receive pins 18 so that said jaws may be detachably secured in the orifices 3, and may be manipulated from open to closed position, and vice versa, and when they are in the open position the handles are in a vertical position and out of the way. The rim 4 is expanded outwardly and upwardly to accommodate said jaws and the coupling-head is also provided with an annular shoulder 19 above the threaded socket 6 to form supports for the jaws 10.

The rims of the jaws may be notched as at 20 and the space between the rim 4 and a vertical drawn from the upper screw-threaded socket 6 is equal to or greater than the space between the notch 20 and the bottom of the jaw, and the orifices 3 are of sufficient dimensions to allow the jaw to be tilted up by downward pressure on the handles 9 so as to allow the notches 20 to engage the rim 4 to sustain the jaws in their up-tilted or retracted position, shown in dotted lines in Fig. 3, thus leaving the space above the screw-threaded socket 6 free to allow the downward passage of the joints between the sucker rod sections.

By reference to Fig. 2 it will be seen that the coupling-head 1 is adapted to serve as an elevator for the sucker rod 14 when the jaws are closed on the ribbed body of the sucker rod, provided the coupling head is unscrewed from the tubing; and that the elevator bail 8 may serve as a wrench handle for the jaws; said jaws serving to prevent the rotation of the sucker rod 13 during the operation of screwing or unscrewing the section of the sucker rod next above. The bail 8 is long enough to swing up over the portion of the sucker rod which projects above the jaws 10 when the sucker rod head is supported by said jaws so that it may readily be used to elevate the sucker rod when the coupling-head 1 is unscrewed from the pump tubing 11.

The upper screw-threaded socket 6 of the coupling head adapts the coupling-head for the reception of the pump head 12, and said pump head is provided with a laterally projecting spout 21, and above said spout with a packing chamber 22 which tapers downward at its lower end and is provided at its

upper end with a screw-threaded seat 23 for the packing gland 24. Inside the said chamber 22 is provided a resilient packing sleeve 25 which is tapered from the middle toward both ends and is reversely slotted from its ends; the slits 26 from one end extending beyond the slits 27 from the other end so that the entire sleeve may be compressed toward its axis. Said sleeve is made of some suitable resilient material such as bronze, brass, fiber. The upper end of the packing sleeve 25 is provided with an annular bead 28 and the gland 24 is provided with a downwardly flaring chamber 29 to receive the upper end of the packing sleeve 25; and the wall of said chamber 29 is provided at a considerable distance above the bottom of the gland, with an annular recess 30 to engage the bead 28 when the gland has been screwed down deeply into the packing chamber 22. Within the packing sleeve 25 there is provided a packing tube 31 which may be of any suitable construction and material within the judgment of the constructor, but is preferably a split tube of some yielding wear-resisting material and which may in some instances be formed by simply slitting longitudinally a short section of rubber hose, as suggested in Fig. 9 where 32 designates the longitudinal slit extending tangentially from the bore to the periphery of the tube. Said tube may also be provided with perforations 33 to allow lubricants to pass to the polishing rod 34 of the pump.

The packing tube 31 is of greater length than the packing sleeve 25 and is of greater diameter than the tapered portion of the chambers 22 and 29, so that the packing will be supported at its lower end by the walls of the packing chamber 22 and will be subject to compression by the downward movement of the gland 24. Said gland is provided at its upper end with projecting screw threads 35 to screw into the seat 23 and said seat 23 is of considerable length in order that the gland may be screwed down from time to time to take up the wear occurring in the packing.

The packing chamber 22 has a cylindrical portion 36 to accommodate the cylindrical lower end 37 of the gland 24 as said gland is screwed down. In practical use said gland may be screwed down until the recess 30 engages the bead 28 and when this occurs the packing sleeve 25 and its contained packing may be drawn up out of the packing chamber 22 by simply unscrewing the gland. As the gland is screwed down, the wall of tapered chamber 29 thereof acting on the upper end of the packing sleeve 25 compresses such upper end onto the packing and tends also to force the packing sleeve downward whereupon the lower taper end of the packing sleeve is, in like manner, compressed by the downwardly tapering por-

tion of the packing chamber 22. By this action the packing is compressed equally throughout its full extent against the polishing rod and the passage-way through the 5 stuffing box is perfectly closed by the compression of the packing between the polishing rod and the stuffing box and gland. The pump head 12 is provided immediately above the spout 21 with an annular shoulder 10 38 between the bore 39 of the head 12 and the packing chamber 22, thus to hold the polishing rod in line with the gland 24.

Referring to Fig. 1 it will be seen that when it is desired to pull the sucker rod, the 15 pump head 12 may be unscrewed from the coupling-head 1; and that when the sucker rod is elevated in the usual manner, the polishing rod 34 will slide up through the head 12 until the joint between the polishing 20 rod 34 and the section 13 of the sucker rod engages the shoulder 38, and then the head 12 will be drawn up off of the head-coupling 1. Then a pair of jaws 10 will be inserted as shown in Fig. 1 and then the 25 handles 9 may be turned up thus bringing the jaws into the position shown in Fig. 2; whereupon the sucker rod may be lowered to the position shown in Fig. 2, and then the upper head 12 may be slid upward out 30 of the way to give access to the coupling 40 between the polishing rod and the sucker rod section 13 so that the joint may be unscrewed from the sucker rod section, the 35 jaws 10 meanwhile serving as a wrench to hold the sucker rod section 13 from turning.

In Figs. 5 and 6 a pair of jaws 10' are shown differing from the jaws 10 in the other figures in that the jaws 10' are provided with tapered faces forming a circular 40 orifice 41 and terminate in a sharp edge 42 adapted to frictionally engage the tube 11 to clamp and hold the same at any elevation as the tubing is allowed to rest at any time during the operation of pulling the 45 tubing. In Fig. 5 the coupling-head 1" is devoid of the screw-threaded seat 6 as said seat is not required in the coupling-heads designed to be screwed onto well casing 43.

In practical work in the oil field it is not 50 necessary to provide a pair of jaw levers for every pump as a single pair of jaw levers may be used successively on all of the pumps of a group. The same is true with regard to the jaws 10' and by use of grip-

ping jaws shown in Figs. 5 and 6 the coupling-head 1" is adapted, when unscrewed from the casing, to serve as a tubing elevator.

I claim:—

1. A head-coupling adapted at its lower 60 end for attachment with tubing and provided at its upper end with jaw seats and with orifices extending from said seats in the rim of the coupling, and tilting jaws in said seats; said jaws being provided with 65 handles extending through said orifices.

2. A head-coupling adapted at its lower end for attachment with tubing and provided at its upper end with jaw seats and with orifices extending from said seats, and 70 tilting jaws in said seats; said jaws being provided with handles extending through said orifices; said jaws being also provided with notches to engage the rim when the 75 jaws are tilted up.

3. The combination with an elevator bail, of a head pivoted to said bail and provided with jaw seats and with orifices extending from said seats; and tilting jaws in said 80 seats; said jaws being provided with handles extending through said orifices.

4. In a pump provided with a sucker rod, the combination with a tubing-head coupling, of an elevator bail pivoted to the head-coupling, and jaws pivotally mounted 85 on the head coupling and adapted to engage the sucker rod to hold the same and to serve as a wrench therefor.

5. The wrench jaw set forth provided with a slot to engage a ribbed sucker rod 90 and also provided with a projection; and a head provided with a seat for said jaw and for said projection.

6. The elevator and wrench jaw set forth provided with a slot to engage a ribbed 95 sucker rod and also provided with a projection; a head coupling provided with a seat for said jaw and for said projection, and a bail pivoted to the head to serve as a wrench handle and as an elevator bail.

In testimony whereof, I have hereunto set my hand at Los Angeles California this 13th day of June 1910.

JOHN HAHN.

In presence of—

JAMES R. TOWNSEND,
L. BELLE RICE.
